US00D526891S

(12) **United States Design Patent** (10) **Patent No.:** **US D526,891 S**
Goldstein et al. (45) **Date of Patent:** **** Aug. 22, 2006**

(54) **DISPENSER FOR PARTICULATE MATERIAL**

(75) Inventors: **Joel M. Goldstein**, Lower Gwynedd, PA (US); **Kenneth Graver**, Perkasie, PA (US)

(73) Assignee: **Aquarium Pharmaceuticals, Inc.**, Chalfont, PA (US)

(**) Term: **14 Years**

(21) Appl. No.: **29/191,887**

(22) Filed: **Oct. 15, 2003**

(51) **LOC (8) Cl.** **09-03**

(52) **U.S. Cl.** **D9/417**

(58) **Field of Classification Search** D9/417, D9/399, 414, 420; D1/112; D18/18, 56; D21/307, D21/308, 340, 478; D24/189

(57) **CLAIM**

The ornamental design for a dispenser for particulate material, as shown and described.

DESCRIPTION

FIG. 1 is a front isometric view of the dispenser for particulate material in accordance with my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.

The broken lines in the figures are for illustrative purposes only and form no part of the claimed design.
